BARBER'S CLIPPERS

Ralph Greco, George Getz, and Frank Marino,
Dover, Ohio

Application April 12, 1934, Serial No. 720,292

1 Claim. (Cl. 30—1)

This invention appertains to new and useful improvements in clippers employed in cutting hair, and more particularly to clippers of the electrically driven type.

5 The principal object of the present invention is to provide barbers' shears wherein means is provided for gauging the depth of the cutting action.

Another important object of the present invention is to provide automatic means for feeding 10 a comb gradually in a forward direction as the clipper is moved upwardly along the head so that the clipper will cut to a lesser depth gradually as it moves upwardly.

These and various other important objects and 15 advantages of the invention will become apparent to the reader of the following specification.

In the drawings:

Figure 1 represents a side elevational view of the improved clippers.

20 Figure 2 represents a bottom plan view of the clippers.

Figure 3 represents a bottom plan view of the clippers, with the bottom section removed.

Figure 4 is a fragmentary longitudinal sec- 25 tional view.

Figure 5 represents a sectional view taken sub-stantially on line 5—5 of Figure 2.

Figure 6 represents a fragmentary detailed sec- 30 tional view showing the pushbutton.

Figure 7 represents an elevational view of the worm rider.

Figure 8 represents a side elevational view of the gear and worm unit.

Figure 9 represents an edge elevational view 35 of the adjustable comb.

Referring to the drawings wherein like numerals designate like parts, it can be seen that the shell of the clipper is made up of the upper section 5 and the lower section 6 and suitable means

40 is employed for securing these sections together and as is clearly shown in several of the views.

The stationary and movable cutter blades 7—8 respectively are mounted at the forward end of the shell, while at the rear end an opening

45 is provided for receiving the conductor cord 9 which leads to the motor, as shown in Figure 4.

The motor includes the field 10, the armature 11 and the armature shaft 12, on which is located the usual motor cooling fan 13 which obtains its

50 air through the port 14 in the top section 5. This port 14 has a guard 15 disposed over the same.

The guard is provided with an extension 16 hav- 55 ing an opening therein through which a screw 17 is disposed and this screw incidentally is

threaded into the bearing block 18 on the inside

of the section 5. This bearing block has one end of the shaft 19 disposed in a recess thereof, while the opposite end of the shaft 19 is disposed into a recess in the bearing block denoted by numeral 20 in Figure 4.

5 Rotatable on the shaft 19 is the unit made up of the gear 21 and the worm 22.

The armature shaft 12 has an extension 23 which is splined in the rear end of the shaft section 24 which in turn is keyed to the worm 25.

10 As is clearly shown in Figure 5, a second gear and worm unit consists of the gear 26 and the worm 27. The gear 26 meshes with the worm 28 on the shaft section 24, while the worm 27 meshes with the gear 21.

15 The aforementioned worm 25 meshes with the gear 29 which operates the eccentric 30. The eccentric 30 in turn operates the lever 40 which is connected to the rocker 41 which actuates the movable blade 8.

20 The bottom of the section 5 is provided with the offset 42 forming a passageway in which slides the shank 43 of the comb 44, this comb being obliquely disposed with respect to the shank 43 and when in retracted position, hugs the forward 25 end of the shell, as in the manner shown in Figure 4.

An eccentric 45 is mounted at the rear end of the offset 42 and operates into the shell to form a stop for the rear end of the shank 43, so that 30 if desired, the comb can be retained in any spaced position with respect to the forward end of the shell.

The rear edge portion of the shank 43 is pro- 35 vided with a pocket 46 therein, in which fits the circular shaped head 47 of the arm 48 projecting laterally from the barrel 49. This barrel 49 is provided with a leg 50 having a lug 51 disposed laterally at its outer end.

40 Numeral 52 represents a thumb button, the shank 53 of which is slidable through an opening in the side of the section 6 against the tension of the leaf spring 54. Numeral 55 represents an elongated stem projecting from the button shank 53 and this extends through the barrel 49 and is 45 provided with a head 56 at its opposite end slid-able through a corresponding opening in the opposite wall of the section 6.

50 A coiled spring 57 is interposed between the arm 48 and the lower portion of the shell sec- 55 tion 6 for normally tending to urge the barrel 48 against the head 56, while the leaf spring 54 in turn serves to maintain the stem 55 urged in a direction so as to maintain the lug 51 of the leg 55 out of engagement with the worm 22.

Numeral 58 represents the slidable switch button for controlling the contactor 9 with respect to the contact 60.

It can now be seen that when the button 52 is forced inwardly, the barrel 49 will move with the same and around the lug 51 to engage into the worm 22. This pushing of the button 52 is generally done just as the clipper is started up the back of the head and as the motor rotates the shaft 24, the speed thereof is reduced through the gears 26-27 so that the worm 22 turns relatively slowly and causes a correspondingly slow motion of the arm 48 which in turn slowly moves the comb 44 outwardly of the forward end of the shell. Thus the clipper blades are gradually fed away from the head as the clipper rides upwardly.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

In a barber's shears comprising a motor, cutter blades, means between the motor and the blades for operating the latter, a comb slidably mounted at the front of the said cutter blades and being provided with a shank, a rockable member having one end engageable with the shank, a worm, step-down gearing from the motor to the worm, manual means for engaging the opposite end of the rockable member with the said worm, said manual means consisting of a pushbutton provided with a stem, said rockable member consisting of a barrel rotatable on the stem and provided with an arm engageable with the comb shank, said barrel being provided with a leg having a lug, said button being adapted to shift the barrel so that the lug will engage into the said worm.
